UNITED STATES PATENT OFFICE.

CHARLES W. UNKLE, OF MONROE, MICHIGAN, ASSIGNOR TO THE GRILEY-UNKLE ENGINEERING COMPANY, OF MONROE, MICHIGAN, A CORPORATION OF MICHIGAN.

TUB BEATER.

Application filed January 2, 1920. Serial No. 348,933.

To all whom it may concern:

Be it known that I, CHARLES W. UNKLE, a citizen of the United States of America, residing at Monroe, in the county of Monroe and State of Michigan, have invented certain new and useful Improvements in Tub Beaters, of which the following is a specification, reference being had therein to the accompanying drawings.

This invention relates to tub beaters such as are commonly employed in the reduction of paper and similar waste material to pulp. The presence of rags, string and similar waste material of a comparatively tenacious character in a tub beater designed primarily for the reduction of paper is a detriment to efficient operation, since the rags, etc. disintegrate much more slowly than the paper and may be treated to much better advantage in a machine especially operated for that purpose. However, it is not commercially feasible to thoroughly sort the charge by the feeder, and consequently, a considerable quantity of rags and the like is apt to accumulate in a beater after it has been operated for some time.

It is the object of the present invention to equip a tub beater with a rag picking device, which may be operated whenever desired to remove any accumulation of rags and like tenacious material from the tub.

A further object of the invention is to provide an operating mechanism for such a rag picker, which will permit the exertion of a considerable effort by manual means without undue labor, and which will act to maintain the rag picker in any desired position which it occupies during removal therefrom of the material which has been separated from that in the tub.

Another object of the invention is to improve the construction disclosed in issued Patent No. 1,244,144 by providing for the introduction of water into the flow box, which is a feature of said construction, so as to prevent the pulp from clogging in the flow box and thus interfering with efficient operation.

In the drawings:

Figure 1 is a plan view of a tub beater improved in accordance with the invention;

Figure 2 is a partial section on the line 2—2 of Figure 1;

Figure 3 is a view of the beater in partial

side elevation, showing the actuating mechanism of the rag picking device;

Figure 4 is a detail in cross section of the rag picker, the section being taken on line 4—4 of Figure 1.

In these views, 1 designates the elongated tub in which the paper or similar material to be pulped is subjected to the disintegrating influence of water or other liquid. Secured in this tub longitudinally is the usual mid-feather 2 of such length and so positioned as to permit the circulation of the material around the tub when said material is impelled at one side of the mid-feather.

The spaces formed within the tub at each side of the mid-feather are designated respectively by the reference characters 2^a and 2^b, and within the space 2^a is located the usual roll 3, formed of suitable material, and carrying knives or fly-bars cooperating with the usual bed plate (not shown) in the bottom portion of the tub. Said roll is fastened to a shaft 4 provided at one end with the belt pulley 5 or other suitable driving member. The tub also contains the usual back fall at 6.

The upper portion of the roll 3 is enclosed in a hood 7, and a portion of said hood, preferably remote from the back fall 6, is perforated, as indicated at 8. Secured on a rod 9, extending parallel to the shaft 4 across said perforated portion is a series of plates 10 having sharp edges, so that when said rod is reciprocated, said plates will cut such portions of the reduced stock as may be protruding out through said perforations, keeping the perforations clear for the passage of the reduced material as is hereinafter further explained.

Reciprocation of the rod 9 is accomplished by a mechanism comprising a pin 11 mounted transversely upon one end of said rod and engaging in slots 12 formed in the slide bearing 13, said pin being engaged by a pitman 14, actuatable by rotation of an arm 15 connected to a worm wheel 16. The worm 17 driving said worm wheel is itself driven by a pulley 18 which is connected by a belt 19 to a pulley 20 mounted upon the end of the shaft 4 opposite to that carrying its drive pulley 5. Thus, it is evident that when the shaft 4 is driven to revolve the roll 3, said shaft transmits a reduced rotation to the worm wheel 16, which latter,

through the arm 15 and pitman 14, continuously reciprocates the rod 9. Owing to the centrifugal effect of the revolving roll 8, stock is thrown against the interior face of the curved portion of the roll, such portions of the stock as are material reduced being thus ejected through the perforations 8. Such large portions of the stock as may tend to clog said perforations are either cut off by the reciprocating plates 10 or pushed back by said plates within the hood.

To the perforated portion of the hood there is secured a casing 21 for receiving the material discharged through the perforations, the bottom of said casing being inclined. At its lower end, said casing is adapted to discharge into an inclined trough or gutter 22, which conducts the material from the hood across the top of the tub 1 where it may enter some suitable receptacle.

The perforated hood 7 in combination with the casing 21, receiving material ejected from the hood through the perforations thereof, and the trough 22 for conducting the material from the casing is disclosed in the Patent 1,244,144. The present invention improves upon said combination by curing a defect which has interfered with efficient operation, namely, the tendency of the pulpy material to accumulate unduly within the casing 21, owing to a lack of sufficient fluidity. To insure a continuous discharge of the material from said casing, the present invention provides a pipe 23 opening into the higher end of the casing for continuously discharging water into the casing during operation of the beater, thus reducing the pulpy mass within the casing to a sufficiently fluid state to insure its passage through the discharge opening of the casing into the chute 22. A baffle plate 24 is preferably arranged in a slightly spaced relation to the discharge end of the pipe 23 within the casing 21 to spread the water so that it will thoroughly wash the upper end wall of the casing and be more efficiently distributed throughout such material as has accumulated within the casing.

A further feature of the invention is the provision of the perforated pipe 25 extending parallel to the shaft 4 through the upper portion of the casing in proximity to the perforated portion of the hood, water being supplied to said pipe through the pipe 25 and being ejected upon the perforated face of the hood to supplement the plates 10 in cleaning pulpy material from said face and to soften such material as clogs the perforations 8 so that the same may be more readily removed by the reciprocating plates.

A rag picker for removing from the tub tenacious material, such as rags, is located in the space 26 and comprises a rock shaft 26 extending parallel to the shaft 4 above the surface of the material in the tub, said

rock shaft having rigidly mounted thereon a row of picker arms 27, the ends of which are curved slightly and preferably pointed. Upon one end of said shaft 26 there is mounted a worm wheel 28, which is actuatable by the worm 29, having upon the shaft thereof a crank disc 30 provided with an elongated handle or crank pin 31. The shaft 26 is preferably of square cross-section except as regards its journal portions, and a rigid mounting of the picker arms 27 on said shaft is accomplished by means of brackets having the rectangular collars 32 for snugly engaging the shaft and the channeled portions 33 wherein the picker arms are engaged and retained by bolts.

In using said rag picker, the operator grasps the handle 31 and, through the worm and worm wheel drive, imparts a gradual rotation to the rock shaft 26, whereby the picker arms 27 are lowered into the material in the tub to any desired extent, but preferably to the substantially vertical position, which is indicated in dash lines in Figure 3. Owing to the circulation of the material in the tub, the direction of which is indicated by the arrows in Figure 1, such material, as by reason of its superior tenacity resists disintegration, lodges against said picker arms and may be removed thereby from the material in the tub by subjecting the shaft 26 to a reverse rotation, whereby the picker arms are returned to their normal horizontal position. The material thus elevated is then removed from the picker arms in any desired manner, this operation being repeated until the material in the tub has been sufficiently cleared of rags and like material.

It is to be noted that by employing worm and worm wheel drive for the shaft 26, the same is held locked in any desired position and more particularly in its raised position which it occupies while being cleared of the material that it has elevated from the tub.

By the employment of the described rag picker, the operation of the beater in reducing the pulpy paper stock is not retarded or uselessly prolonged by the presence of rags and like material in the stock which is fed to the tub.

What I claim as my invention is:

In a paper pulping machine, the combination with a beater drum, of a hood for said drum perforated for the discharge of material from the drum, a casing secured to the perforated portion of the hood to receive the discharged material, and a pipe opening into said casing for supplying a liquid thereto to facilitate the discharge of the material from the casing, and a baffle plate within said casing opposite the outlet of said pipe.

In testimony whereof I affix my signature.

CHARLES W. UNKLE.
